United States Patent Office.

GEORGE BUNTIN, OF EAST BOSTON, MASSACHUSETTS.

Design No. 2,609, dated April 2, 1867.

DESIGN FOR THE END FRAME OF A CAR SEAT.

The Schedule referred to in these Letters Patent and making part of the same.

TO ALL PERSONS TO WHOM THESE PRESENTS SHALL COME:

Be it known that I, GEORGE BUNTIN, of East Boston, in the county of Suffolk, and State of Massachusetts, have invented or produced a new and useful Design for a Railway Car Seat End Frame, and do hereby declare the same to be fully described in the following specification, and represented in the accompanying drawings, of which—

Figure 1 is a front elevation.

Figure 2, an end elevation; and

Figure 3 a vertical section of a railway-carriage seat with its end frame formed in accordance with my design.

In the drawings, A is the seat, and B the reversible back thereof. The seat rests on two supporting bars, *a a*, one being underneath its front and the other being underneath its rear part. These bars are tenoned and fastened into socketed projections, *s s*, extending from the end frame C. Other or foot-rest bars, *b b*, are arranged below the seat, and in socketed projections, *t t*, extending from the end frame. The arm-rest of the frame C is shown at *c*. It is arranged wholly on one side of a vertical plane passing through the most projecting part *d* of the frame, the frame being bent back as shown at *e*, as it rises up from the seat. In descending below the seat, the frame also has another bend, (as shown at *f*, in figs. 1 and 2,) which extends down to the foot-bar holders *e e*. From thence the frame extends vertically downward. The form of the said end frame, in side and edge views, is given in the drawings.

I claim, as my invention, the design for a car seat end frame, as hereinbefore described, and as exhibited in the above-mentioned drawings.

GEORGE BUNTIN.
